DEVICE FOR USE IN COLORING FLEXIBLE ARTICLES

Nelt Barr and Randolph J. Dorn, Sandusky, Ohio,
assignors to The Barr Rubber Products Company, Sandusky, Ohio, a corporation of Ohio

Application October 18, 1929. Serial No. 400,512

4 Claims. (Cl. 8—19)

This invention relates to a device for use in connection with the coloring of flexible articles and has for its primary object to produce a device which is simple in construction, economical to manufacture and efficient in operation.

A further object of the present invention is to provide a device whereby the expense in connection with the production of articles of this particular character can be reduced to a minimum and at the same time the resultant article has a materially improved appearance over articles of similar character.

With the objects above indicated and other objects hereinafter explained in view, the invention consists in the construction and combination of elements hereinafter described and claimed.

Referring to the drawing,

Fig. 1 illustrates a balloon produced in the device.

Fig. 2 illustrates a device, part of which is broken away and by which the balloons may be produced.

Fig. 3 is a top plan view of the device shown in Fig. 2 and part of which is broken away.

While the device embodied in connection with coloring articles hereinafter referred to may be employed in connection with a variety of flexible articles, the description herein will refer specifically to the preferred construction of the device as adapted for use in connection with the coloring of rubber balloons, which is one of the flexible articles adapted to be produced therein and it is to be understood that the invention is not limited to the use of this particular device as changes and modifications may be resorted to without departing from the spirit of the invention as defined in the appended claims.

In the drawing, the container, which is designated 10, is of metal or other suitable material and comprises end members 11, a back 12 and a bottom 13, all preferably formed integral, and of any desired size or shape. The bottom 13 has a transversely extending opening 15 of a diameter substantially the depth of the bottom 13. A tubular member 16, closed at its upper end, has its lower open end disposed within the opening 15 and may be attached to the bottom 13 adjacent the opening 15 by soldering or any other suitable means. The tubular member 16 extends upwardly within the container 10 and to a position adjacent the upper portion of the container for a purpose to be later described.

The container 10 is further provided with a front cover member 17 which is pivotally con-

nected along one of its edges to one of the end members 11 by means of hinges 18a. Adjacent the opposite edge is attached a hasp 18 which cooperates with an eye 19 secured to the adjacent end member 11 for retaining the front cover 17 in closed position.

A top member 20 is hingedly connected at 21 to the upper end of one of the end members 11, while the opposite end has attached thereto a hasp 22 for cooperating with an eye 23 secured to the adjacent end member 11 to retain the top member 20 in closed position. A handle 24 is attached preferably to the top member 20 for the purpose of enabling the container to be moved about conveniently and during the dipping operations.

The entire container 10 is preferably perforated as at 25 as well as the tubular member 16 to thereby permit the coloring solution to have ready access to the interior of the container 10.

The tubular member 16 divides the container 10 into two compartments 26 and 27, which receive the balloons 28 or other flexible articles to be colored.

With the front cover 17 closed but the top member 20 open, balloons 28 or other flexible articles are placed promiscuously and in irregular crumpled condition within the compartments 26 and 27 until they are entirely filled, at which time the member 29 having transverse openings 30 is placed within the top of the container 10 for contact with the mass of assembled balloons or other assembled articles. The top 20 is then closed and fastened thereby retaining the member 29 in proper position with relation to the balloons 28 to thereby produce sufficient pressure to hold the balloons 28 in this irregular crumpled condition. In this condition, the container 10 with its contents, is submerged in the coloring solution which readily reaches the balloons or other flexible articles through the perforations 25.

The following is a brief description of the method employed in connection with the coloring of flexible articles, such as balloons, in which the device heretofore described is used in carrying out the method. The method is fully disclosed in our copending application Serial No. 400,511, filed October 18, 1929, to which reference may be had for a more clear understanding of the method.

It should, of course, be understood that the flexible articles or balloons, in the present instance, to be colored are first treated with a suitable solution, preferably caustic soda, which contacts with the articles in such a manner as to

prevent any appreciable running or spreading of the dyes when applied to the articles to thereby produce sharp clear lines upon the resultant articles, as well as blended colors and, further-
5 more, to retain a clear portion of the base color of the article.

It is understood, of course, that one or more colors may be applied to the flexible articles or balloons, while in this irregular crumpled condition, with the same result of producing upon the article, when released and removed, an irregular configuration of which no two articles or balloons are alike.

In the preferable procedure, however, three colors are employed; namely, yellow, red and blue, which colors are in the form of oil soluble dyes mixed with naphtha to produce the proper solution. The container with its contents, in this irregular crumpled condition, is preferably first 10 submerged in the yellow coloring solution, immediately withdrawn, permitted to drain until the majority of the coloring solution has run off, submerged in the red coloring solution, immediately withdrawn, permitted to drain off as 15 before, and subsequently submerged in the blue coloring solution, immediately withdrawn, and permitted to drain. This operation continues depending upon the number of colors it is desired 20 to apply to the flexible articles or balloons. The 25 container is then opened, and the flexible articles or balloons removed with the result that the articles are substantially covered with an irregular configuration of various colors of which no two articles have identically the same design.

30 35 Having thus described my invention, what we claim is:
1. A device for use in colorizing flexible articles comprising a perforated container having a pivoted cover, a perforated hollow member disposed within said container and dividing the latter into article receiving compartments, and a member fitting within the top of said container and extending substantially over said compartments, said member being maintained in 40 45 place by said cover.

2. A device for use in coloring flexible articles comprising a perforated container having a pivoted cover and a pivoted side, latching means for said pivoted cover and said pivoted side, an opening in the bottom of said container, a hollow open end perforated member disposed within said container and dividing the latter into article receiving compartments, the open end of said member being associated with said opening, and a member fitting within the top of said container and extending substantially over said compartments, said member being maintained in place by said cover.

3. A device for use in coloring flexible articles comprising a substantially rectangularly shaped perforated container open at its upper end through which articles are introduced into said container, said container having an opening in the bottom thereof, a perforated cover pivotally connected to said container and adapted to close the upper end of the latter, and a hollow perforated member disposed within said container perpendicular to the bottom of the latter, said member having one end secured to the bottom of said container in alignment with the opening and the opposite end terminating adjacent said cover and dividing said container into article receiving compartments.

4. A device for use in coloring flexible articles comprising a perforated container open at its upper end and having an opening in the bottom thereof, a perforated cover pivotally connected to said container and adapted to close the upper open end of the latter, said container having one of its side walls pivotally connected, means for securing said side wall in closed position, and a hollow perforated member disposed within said container perpendicular to the bottom of the latter, said member having one end secured to the bottom of said container in alignment with the opening and the opposite end terminating adjacent said cover and dividing said container into article receiving compartments.

NELT BARR,
RANDOLPH J. DORN.
